COMBINATION CROSSING GATE AND SIGNAL PROTECTIVE MEANS

Harry C. Sampson, Bloomington, Ill.

Application May 22, 1937, Serial No. 144,131

8 Claims. (CL. 246—130)

This invention relates to protective means for a highway railroad crossing.

In the past, many mechanisms have been proposed for the purpose of protecting traffic at railroad crossings. Among such mechanisms are found gates which are lowered across the highway either manually or by electromotive power, audible signals such as bells, visual signals in the shape of warning words sometimes made up of reflecting units adapted to be lighted at night by approaching vehicles, or by flashing signal lights; or combinations of both audible and visual signals.

The various railroads and many State and inter-state commerce commissions have given much attention to the elimination and/or protection of grade crossings, and the U. S. Government has furnished large sums of money which have been and are being devoted to the complete elimination of dangerous grade crossings, and protecting others. In many cases where the elimination of grade crossings is impractical or immediately impossible, standard types of warning signals have been and are being installed as fast as possible, but it has been found that even after these audible and/or visual warnings and signals have been installed, serious accidents have occurred at these same crossings.

After many years of close association with and study of this matter, I have worked out what now seems to be a solution of this highly important and vexatious problem. Thus the object of my present invention may be generally stated as that of bringing about a new combination of mechanisms which will make the vehicle driver or pedestrian conscious of the fact that there are safety devices in front of him for his protection, and to compel observance thereof.

Another object of my invention is to provide a railroad crossing protective means which will efficiently prevent crossing accidents.

Other and further objects will be discerned by one skilled in this art, from a reading of the specification taken in connection with the annexed drawings, wherein:

Figure 1 is a front view of the track side of my combined crossing gate and signal device, the crossing gate being shown in "clear" position, the extremity of the gate being set beside the heel portion of the gate in order to get the view on the drawing.

Figure 2 is a view of Figure 1, looking from right to left.

Figure 3 is a view similar to Figure 1, but from

the "approach" side of the mechanism, with the gate in "stop" position.

Figure 4 is a view of Figure 3, looking from right to left.

Figure 5 is a diagrammatic view showing how the structure of Figures 1 to 4 inclusive are installed at a highway railroad crossing.

Figure 6 is a diagram of the control apparatus used in connection with the structure of Figures 1 to 4 inclusive, the parts being in normal clear position.

Figure 7 is a diagram similar to Figure 6, but showing the gate and signal devices in part of their cycle of operation.

Referring now to the details, wherein like numbers refer to corresponding parts in the various views, 1 is a standard usually referred to as a mast, having a base 2 usually fastened to a concrete foundation. The mast 1 carries the usual warning sign 3 fastened thereto in any satisfactory manner as by U-bolts 4. The sign 3 has depicted thereon a warning caption such as "stop" or "stop on red signal", the letters of which are made up of small light-reflecting units 5. Also, the mast carries an additional sign 6 fastened thereto by the same type of U-bolts 4 and having the number of tracks designated thereon, indicating the number of tracks being protected by the crossing signal, these designations being made up of similar units 5. The mast also carries arms 7 and 8 having the words "railroad crossing" thereon, the letters of the words being made up of the same devices 5 heretofore referred to. At the top of the mast 1 is positioned an electrically operated bell or gong 35 G. This mast also carries a satisfactory fastening means 9 for supporting lights 10 and 11, each having a hood 12 and a back-ground disc 13.

Toward the base of the mast 1 is an attachment member 14 supporting a box or container 15 within which are carried operating means for the gate. The gate comprises a heel or base portion forming a mounting plate 16 which may be made of a suitable piece of material, such as steel, of proper thickness, to which is fastened, as by bolts 17, a hub casting or bearing support 18 to receive a shaft 19 extending from the box 15. Preferably, the mounting plate 16 has fastened thereto, on opposite sides, in any satisfactory manner, as by rivets 20, pairs of spaced angle irons 21 and 22, between which, and on opposite sides of the plate 16, is positioned the end of a gate arm 23 which is preferably composed at this end of two boards 24 and 25 located on opposite sides of the mounting plate 16, and be-

tween the respective angle irons 21 and 22, and bolted to the plate 16 by suitable bolts 26. As will be seen by reference to Figures 1 and 2, the boards 24 and 25 taper from the mounting plate 16 toward the end of the arm, the boards terminating at a point 27.

Extending between the outer ends of the arm members 24 and 25, is a single board 28, being fastened between the ends of the boards 24 and 10 25 as by bolts 29. Intermediate the ends of the arm members 24 and 25, is a spacing block 30 held in position by bolts 31. This gives an arm construction which is relatively light, yet sturdy, the idea being that if a motor vehicle should hit 15 it when it is in lowered position, the arm will break off without damage to the mounting plate or operating mechanism.

Mounted on the arm 23, are a plurality of lamps 32, 33 and 34, preferably of light-weight 20 construction, such as aluminum. The lamps 32, 33 and 34 are preferably provided on opposite sides with optical type of red lenses of suitable diameter which I have found, in practice, to be approximately three inches, so that the lamps 25 can be seen from both directions on the highway.

In my present system of safety protection, I prefer to make the arms 23 of a length which will not quite reach the center of the highway, but which is long enough to block the lane or 30 lanes of approaching traffic, as is indicated in Figure 5, which shows two signal structures erected on opposite sides of the railroad, on the approach side of the track only, whereby highway vehicles which should happen to pass the gate 35 arm, just as it is being lowered, can proceed across the tracks, as they are not blocked from leaving the tracks, since there is no combination signal and gate arm on the far side of the tracks for the traffic lane or lanes in which the vehicle 40 is traveling. As will be pointed out later, the timing is such that should a vehicle just barely get by the signal and gate as the gate arm is descending, there is sufficient time period before the train reaches the crossing for the vehicle to proceed 45 over the tracks, there being no gate on the leaving side, as just described.

It may also be mentioned, by reference to Figure 5, that should for any reason the gates be left down, with no train approaching, due to power 50 failure or other causes, the driver may be able to drive around the end of the gate arm, provided, of course, that the central part of the highway is available for driving purposes; that is to say, a highway in which the traffic is not divided.

The gate arm on each side is preferably painted 55 in diagonal stripes of red and white, or black and white, in which case each of the black stripes has thereon a diagonal row of a plurality of light-reflecting buttons 5, similar to those previously referred to.

The mounting plate 16, carrying the gate arm 23, has an arm 35 having a slot 36 therein to receive a bolt 37 used to fasten weights 38, one on each side of the plate 16, for counter-balancing the arm. By adjusting the weights 38 through the medium of the slot 36, a balance can be obtained such that approximately the same torque is required for operation of the gate arm as that required to operate a semaphore signal. 65 Thus, in my new combination, the initial cost and the cost of operation is held to a minimum because I have found that I can use the same type and size of signaling mechanism that is now used in the operation of semaphores, since the 70 75 turning moment, due to the weight of the arm,

is far in excess of the turning moment due to the counter-weight when the arm is vertical or in clear position; but as the gate arm descends, the moment of the counter-weight increases faster than that of the arm so that the result moment 5 becomes less and less until the arm reaches the horizontal or stop position, at which time the turning moment of the arm per se and counter-weight is practically equal. This feature insures 10 relatively quick starting of the arm downward when the current is cut off the holding coil as will be later explained, and also insures the lowest torque when starting the arm upward on application of current to the motor to raise the arm. Furthermore, the high turning torque at the start 15 of the arm from clear position rapidly turns the motor in reverse direction and generates a counter E. M. F. which quickly produces a snubbing action at the start, as will be later explained. Stated in another way, the counter-weight is so 20 positioned that the gate arm falls rapidly for the first few degrees, such as the order of five, and then at practically constant speed after the snubbing action takes effect as the motor picks up in speed. The gearing itself also applies a 25 certain snubbing action.

The motor, shown at M, in Figures 6 and 7, is geared through a train of gears to a quadrant 39 carried by the operating shaft 19, a slip-clutch 40 being used either between the last pinion 41 and 30 its associated gear 42, or at any other point in the gear train, the object of which will be later pointed out.

The mast 1 has fastened thereto an arm 43 carrying a U-shaped stirrup or support 44 which 35 is adapted to receive the end of the arm 23 when in "stop" position. While the outer end of the gate arm may be provided with a swinging strut or support to engage the surface of the roadway when the gate arm is in stop position, I have not 40 found it necessary to use this.

Coming now to the operation of my combination gate and signal mechanism, and referring first to Figure 6, in which the gate arm 23 is in clear position, it will be seen that the coil of the 45 track relay T is normally energized; that is to say, it operates on a closed circuit so that the contact 45 is normally closed when no train is approaching the crossing. This passes current from the battery B through the slow-release relay S 50 and the common return wire R, back to the battery, thus holding the relay S so that the contacts 46 and 47 are closed while the contact 48 is open.

Another circuit may be traced from the battery B through the contact 49 and conductor 50 to the 55 "hold-clear" magnet HC. Associated with the HC magnet is a pawl 51 and ratchet wheel 52 carried on the shaft of the motor M, and as indicated, the pawl and ratchet are locked so that the motor shaft cannot turn, and likewise the 60 gears connected thereto, thus holding the gate arm 23 in clear position. It will be observed that a parallel circuit through the conductor 53, through the contact 47, is provided to the conductor 50, the reasons for which will be later 65 pointed out. It will also be observed that the conductor 50 passes current to the conductor 54 leading to the motor, but the motor circuit through the conductor 55 is open at the controller rings c₄, c₅, it being understood that all the controller rings c₁ to c₅ inclusive are carried on or directly operated at the same speed of rotation as the shaft 19 carrying the gate arm 23.

Assuming now that a train is approaching the crossing at which the gate and signal mechanism 75

is installed, as soon as the train enters the block, the relay T is short-circuited and thereby de-energized, allowing all the four armature contacts associated therewith to drop into the position shown in Figure 7. The opening of contact 5 opens a circuit through the relay S, but this being a slow-release relay, the contact 46 is held closed as in Figure 6. De-energization of the relay T closes the contact 56 and current passes 10 through relay D, which has a slow pickup as well as a slow release, through the contact 46 to the common return R. The relay D will therefore operate to close the contact 57 before the contacts 46 and 47 are opened so that current will still be 15 applied from the battery B to the contact 57 and conductor 50, through the HC magnet, thereby holding the gate arm in clear position. When the contact 58 is closed, current is applied through the conductor 59 (see Figure 6) to the controller 20 ring c₃ and through the bell or gong G to the common return R. The gong starts ringing at once to give the vehicle traffic a warning and an opportunity to proceed rapidly past the gate and signal combination, or to stop before reaching the 25 signal, depending on the speed at which the vehicle is traveling, and its position at the time the bell starts to ring.

When the contact 60 is closed simultaneously (see Figure 7) with the closing of contact 58, current is also applied to the conductor 61 and passes through flashing-relay-control winding 62, causing contact arm 63 to alternately contact with the contacts 64 and 65, thereby alternately passing current from the winding 71 of a power 35 supply transformer, having a primary 72, through the contact 69 of "power-off" relay 70, through conductor 68, contact 67 and conductor 66, to the contact arm 63; thence through the contacts 64 and 65, alternately through the lights 10 and 11, 40 causing them to flash in accordance with the energization of the windings 62 and 73, which are alternately energized through the contacts 77 and 78 as the contact arm 79 alternately contacts therewith. At the same time, the contact arm 80 45 alternately closes circuits through the contacts 81 and 82, with the lamps 32 and 33 on the gate arm 23, flashing these two lamps practically simultaneously with the flashing of lamps 10 and 11.

50 Thus an audible and visual signal is transmitted to warn an approaching highway driver that a train is approaching and that the gate is about to descend.

After the contact 45 is opened, the slow-release relay S opens the contacts 46 and 47, after a pre-determined time, at the same time closing contact 48, thereby placing a short circuit across the relay D which further assists in slowing up the release of this relay. The actual release time of the relay S is greater by a fraction of a second 55 than the pickup time of relay D, so that the contact 57 is closed before the front contacts 46 and 47 are opened, which holds the HC magnet still in locked position.

60 After the contact 46 is opened, the relay D requires an appreciable time of approximately two seconds, at normal voltage and temperature, before its armature will release to open the contact 57, but when the contact 57 does open, current is removed from the conductor 50 and the HC 65 magnet is de-energized, allowing the pawl 51 to drop away from the ratchet 52, which withdraws the holding force from the arm 23 which starts to fall to stop position by its own weights as previously described. When the contact 67 closes,

current is passed through the contact 67, conductor 66, conductor 75, conductor 76, to the lamp 34 on the end of the arm. This lamp then burns steadily as long as the track relay T is de-energized.

5 This time delay in starting the gate descending, after the gong has started ringing, and the lights 10, 11, 32 and 33 started flashing, gives the driver of a vehicle sufficient time to get across the track before the gate obstructs the highway, assuming 10 that he is in close proximity to the signal mechanism at the time the signals are started into operation.

15 As soon as the gate arm 23 starts to move downwardly in the manner heretofore explained, the controller rings, which are carried in the box 16 and mounted on the shaft 19, or mounted so as to be driven by the shaft 19 at the same speed of rotation thereof, start to turn in the direction of the arrow (see Figure 6). The controller rings 20 c₁, c₂ close circuits, which are normally open as indicated, after the arm moves approximately five degrees in its downward course, thereby completing the following circuits:

25 First, a parallel circuit around the contact 67; 25 and second, a parallel circuit around the contact 60, for reasons which will be later explained.

30 The controller ring c₃ holds the circuit through the gong G approximately 88 degrees of downward movement of the arm 23, and thus the controller ring c₃ opens this circuit by way of the gap 83, about two degrees before the gate arm reaches the stop position. This stops the gong G from ringing, since the ringing might be objectionable should the arm 23, by a failure of power 35 or some other reason, be held in stop position, which would make the continuous ringing of the gong very objectionable where the signals are placed near habitation. It will also be noticed, from Figure 6, that the contacts at the controller 40 rings c₄ and c₅ will be closed in about one or two degrees of downward movement of the gate arm from clear position, thereby establishing a circuit from the motor through the conductor 55, whereby the motor will be ready to function 45 when current is subsequently applied to the conductor 54.

50 After the train leaves the block or moves to a point where the "short" is removed from the relay T, this relay is actuated, closing the contacts 45, 50 49 and opening the contacts 58, 60 and 67. Closure of contact 45 will cause current to pass from the battery B through the relay S, which closes the contacts 46 and 47, applying current through the conductor 50 to the HC magnet, and through the conductor 54 to the motor M. Through the conductor 55 and control rings c₄ and c₅ (see Figure 6), the motor at once starts into operation, and through the gear reduction, the arm 23 is turned to upright or clear position, it being understood that in the rotation of the motor, the pawl 51 slides over the teeth of the ratchet wheel 52, which will then turn in the direction of the arrows in Figure 7.

60 Similarly, the controller rings c₁, c₂ and c₃ are 65 returned to the position indicated in Figure 6, ready for the next cycle of operation, but in this return movement, the contacts on the rings c₁ and c₂ do not open the circuit through the lights until about five degrees before the arm reaches 70 its vertical or clear position, thus keeping the signals in operation until the gate no longer obstructs the highway.

75 When the gate arm reaches approximately 89 degrees in its upward turning movement, the 75

controller rings c_4 and c_5 open the circuit to the conductor 55 at the gaps 84, but the momentum of the arm will carry it the rest of the way to full clear position, where it will be held by the HC magnet to which current will be supplied by the closure of the contact 41.

It may be mentioned that the snubber 85 may be in the form of a single-wave rectifier so that when positive battery is flowing toward the motor 10 on wire 54, the current cannot flow through the rectifier and must therefore flow through the motor. When the motor is acting as a generator in the downward movement of the gate arm, then the polarity is reversed and the positive energy 15 generated will be in reverse direction from the motor, and the rectifier or valve will permit current to flow therethrough, thus short-circuiting the motor which is then being operated by the gate arm as a generator.

20 As an alternative, a pair of normally open contacts may be bridged across the motor terminals and closed by the pawl 51 when it is released by the HC magnet.

It may also be remarked that the clutch 40, 25 being of the slip type, is adjusted so that should the gate arm become caught on the ascent, whereby it could not be raised to a point where the controller or circuit breaker would cut off the motor, the clutch will slip and allow the motor to 30 turn slowly, even though the gate arm does not move. This will prevent burning out the motor which might occur if it were completely stalled.

It may be noted that the power supply and 35 control relays within the dotted line 86 are placed in any satisfactory housing at any suitable place, and the conductors led to the hollow mast 1 by suitable ground cables, those going to the box 15 passing from the mast 1 through a conduit 87; and those to the lights 10 and 11, through junction box 9, and by cables 88 and 89, and from the box to the gate arm likewise through the cable 90.

A rectifier 91 is connected to a secondary winding 92 of the power supply transformer and furnishes what might be termed a trickle charge to 45 the storage battery B; but where a steady power supply is available, the relay 70 is used to furnish current to the contact 69 for the operation of the lights and the flasher control devices F. Should for any reason the AC power supply be 50 cut off, the relay 70 will be de-energized, closing a contact 93, thereby supplying current to the conductor 68 from the battery B. Other arrangements of power supply may be used in place 55 of those indicated.

55 Likewise, a four-pole switch for manual control may be substituted for the four contact arms operated by the relay T, if it is desired to manually control the safety signal apparatus heretofore described. In addition, the track relay controls may be varied to suit conditions, but these form no part of my present improvement in safety control, except the time delay features in the operation of the crossing signals which I believe to be new.

60 The operation of the gate arm and the relays D and S, to provide the time delay feature described, is entirely on the closed circuit principle, so that the failure of power, or the failure of any relay to remain in closed position from any cause whatsoever, will cause the gate arm to descend by gravity, for lack of current, to the HC coil. If the relay D fails to pick up, for any reason whatever, when relay T is de-energized, 65 there will be no failure of the gate arm to de-

70 scend but simply a shortening of the time delay period by the release delay time period of relay D.

75 It may be mentioned, in passing, that the arrangements herein described are very economical in current consumption. The relay S is of comparatively high resistance, of the order of 500 ohms or more, and therefore consumes little energy. While the relay D is of comparatively low resistance, on the order of 50 to 100 ohms, 10 this relay is only actuated for a period of about two seconds or less, or while the relay S is releasing, after the relay T has been de-energized by the approach of a train, or the manipulation of a switch.

15 From what has been said, it will be readily appreciated that I have provided a combination protective mechanism which is a decided improvement over anything heretofore proposed, and which offers special protection in the prevention of disastrous accidents which many times happen to drivers of highway vehicles who are approaching or have been waiting for the passage of a train, and who start across the tracks immediately after the rear of the train has passed 20 over a crossing of the multiple-track type. In such cases, a train approaching on the second track, is obscured by the receding train on the near track, and the impatient vehicle driver, as soon as he sees the rear end of the train on the 25 near track leaving the highway, starts across without seeing the other approaching train.

30 My combination protective mechanism, I think will go exceedingly far toward preventing such accidents, because the gate arm effectively prevents vehicles from proceeding onto the tracks until the way is clear and it is safe to proceed. Furthermore, the flashing lights on the gate arm are right out in front of the driver of the vehicle where they cannot be overlooked, even by the 35 driver's intent observation of the receding train.

35 It will be understood that various changes may be made in the details of my invention; for example, the parts 16, 18, 21 and 22 may be made in one piece, such as a malleable casting, in 40 which case a part of the weight 38 may be cast integral therewith, leaving only a small portion of the weight to be applied in an adjustable manner.

45 While, as has been previously stated, the controller rings c_1 to c_5 may be mounted on the shaft 19 or mounted to be driven by the shaft 19 at the same speed of rotation thereof, this is not necessary as long as the speed of the controller is proportional to the speed of the shaft 19 or 50 movement of the gate arm. For example, in some cases it may be desirable to operate the controller at twice or even four times the speed of the shaft 19 in order to obtain closer adjustment by having the controller rings travel through 55 360 degrees, while the gate arm travels through approximately 90 degrees. It may be noted that, in actual practice, the contact arms 63 and 80 never come to rest in the position shown in 60 Figure 6. The flasher F is ordinarily so designed as to cause the said contact arms to remain in engagement with the contact points last touched before the power is cut off. This is done so that should the flasher F fail to start, due to battery 65 failure or other causes, a part of the lights at 70 least will be lighted.

75 In some cases the bell or gong G may not be needed as the flashing lights will give all the warning necessary. Also, the gate arm per se may be made of one piece in place of the two

pieces 24 and 25 as heretofore described, but all such changes similar to those above indicated are believed to come within the spirit of my invention and the scope of the appended claims.

5. What I claim is:

1. Protective means for a highway-railroad grade crossing including in combination; an elevated mast carrying thereon devices for conveying a warning, a gate arm mounted near the bottom of the mast on a shaft for rotation in a vertical plane and provided with gravity-controlled means for governing the descent of the gate arm, additional warning devices on the gate arm, a motor connected through a reduction gearing to the gate arm shaft and having a control circuit therefor, holding means for the gate arm including a hold-clear magnet, slow-release means for controlling the magnet, a track section and a track relay electrically connected thereto, said relay establishing energizing circuits for the warning devices on both the mast and gate arm and actuating the slow-release means when a train approaches the crossing, a circuit controller operatively connected to said gate arm shaft and having contacts some of which are normally open and being closed when the gate arm starts to lower, certain of said normally open contacts being in said motor circuit and certain other of said normally open contacts acting to establish circuits in multiple with certain of said circuits established by said track relay for said warning devices on the gate arm and certain of the warning devices on the mast, whereby the last-mentioned warning devices on the gate arm and mast are operated before the gate arm starts to lower, said warning devices on the gate arm and certain of the warning devices on the mast continuing to operate until after the track relay is restored to normal position when the train passes from said track section, the motor then acting through its control circuit to restore the gate arm to clear position, the motor circuit and said multiple circuits being opened by the controller contacts just prior to the time the gate arm reaches its clear position.
2. Protective means for a highway railroad crossing including in combination, warning signals including some of the visual type, a mast carrying certain of said warning signals including those of the visual type, a gate arm pivotally mounted in close cooperative relation to the mast and normally held in clear position but arranged to fall by gravity and extend over at least a part of the highway, the gate arm carrying the remainder of the warning signals of the visual type, means including a track relay controlled by the approach of a train for initiating, by said warning signals, a prewarning signal that the gate arm is to fall, means for releasing the gate arm a predetermined time after the pre-warning signal is given, means for intermittently operating the visual signals on the mast and at least some of those on the gate arm, and motor means controlled by said track relay for moving the gate arm back to clear position after the train has left the crossing, at least some of said visual signals being maintained in operation until just before the gate arm reaches its clear position.
3. Protective means for a highway railroad crossing including in combination, warning signals including some of the visual type, a mast carrying certain of said warning signals including those of the visual type, a gate arm pivotally mounted in close cooperative relation to the mast and carrying the remainder of the warning signals of the visual type, means for normally holding the gate arm in inoperative or clear position, said gate arm descending by gravity when released and being of a length to block only the lane or lanes of approaching traffic on the highway, control means for putting the said warning signals into operation on approach of a train to the crossing before the gate arm is released, means operated by said control means for releasing the gate arm a predetermined time after said warning signals are put into operation, means for maintaining the visual signals during the time the gate arm is falling and while in operative position and until the gate arm is restored nearly to clear position, and means for stopping any audible signals approximately as the gate arm reaches its operative position, and means including a motor for moving the gate arm back to inoperative or clear position after the train has left the crossing, in which position the gate arm is again held by said holding means.
4. Protective means for a highway-railroad grade crossing including in combination; a mast, a gate arm mounted near the bottom of the mast on a shaft for rotation in a vertical plane and provided with gravity-controlled means for governing the descent of the gate arm, warning devices on the gate arm, a motor connected through a reduction gearing to the gate arm shaft and having a control circuit therefor, holding means for the gate arm including a hold-clear magnet, slow-release means for controlling the magnet, a track section and a track relay electrically connected thereto, said relay establishing energizing circuits for the warning devices on the gate arm and actuating the slow-release means when a train approaches the crossing, a circuit controller operatively connected to said gate arm shaft and having contacts some of which are normally open and being closed when the gate arm starts to lower, certain of said normally open contacts being in said motor circuit and certain other of said normally open contacts acting to establish circuits in multiple with certain of said circuits established by said track relay for said warning devices on the gate arm, whereby the last mentioned warning devices on the gate arm are operated before the gate arm starts to lower, the said warning devices on the gate arm continuing to operate after the track relay is restored to normal position when the train passes from said track section, the motor then acting through its control circuit to restore the gate arm to clear position, the motor circuit and said multiple circuits being opened by the controller contacts just prior to the time the gate arm reaches its clear position.
5. Protective means for a highway-railroad grade crossing including in combination; stationary signal means including lights, a gate arm shaft, supporting means therefor, a gate arm mounted for movement in a vertical plane and provided with gravity-controlled means for governing the descent of the gate arm, additional warning devices on the gate arm, a motor connected through a reduction gearing to the gate arm shaft and having a control circuit therefor, holding means for the gate arm including a hold-clear magnet, slow-release means for controlling the magnet, a track section and a track relay electrically connected thereto, said relay establishing energizing circuits for the stationary warning devices and the warning devices on the gate arm and actuating the slow-release means

when a train approaches the crossing, a circuit controller operatively connected to said gate arm shaft and having contacts some of which are normally open and being closed when the 5 gate arm starts to lower, certain of said normally open contacts being in said motor circuit and certain other of said normally open contacts acting to establish circuits in multiple with certain of said circuits established by said track relay 10 for said warning devices on the gate arm and certain of the stationary warning devices, whereby the warning devices on the gate arm and the stationary warning devices are operated before the gate arm starts to lower, the said warning 15 devices on the gate arm and certain of the stationary warning devices continue to operate after the track relay is restored to normal position when the train passes from said track section, the motor then acting through its control circuit 20 to restore the gate arm to clear position, the motor circuit and said multiple circuits being opened by the controller contacts just prior to the time the gate arm reaches its clear position.

6. Protective means for a highway-railroad crossing including in combination; stationary 25 warning devices, a mast, a gate arm shaft on said mast, a gate arm mounted on said shaft for rotation in a vertical plane and provided with gravity-controlled means for governing the 30 descent of the gate arm, additional warning devices on the gate arm, a motor connected to the gate arm shaft and having a control circuit therefor, holding means for the gate arm including a hold-clear magnet, slow-release means 35 for controlling the magnet, means to establish energizing circuits for the warning devices and actuating the slow-release means, a circuit controller operatively connected to said gate arm shaft and having contacts some of which are 40 normally open but are closed when the gate arm starts to lower, certain of the normally open contacts being in said motor circuit and certain other of said normally open contacts acting to establish second energizing circuits thru certain 45 of said warning devices on the gate and of the stationary warning devices, whereby the warning devices are operated before the gate arm begins to lower, the said certain warning devices continuing to operate after said means to establish 50 energizing circuits thru said warning devices is restored to normal position and has opened such circuits, the motor then acting thru its control circuit to restore the gate arm to clear position, the motor circuit and said second energizing circuits being opened by the controller contacts just 55 prior to the time the gate arm reaches its clear position.

7. Protective means for a highway-railroad grade crossing including in combination; stationary 60 warning signals, a gravity-closed gate arm pivoted for movement in a vertical plane, and warning signals on said arm, a normally energized track relay controlled by approaching

trains, energizing circuits for said signals controlled by said track relay, gate-arm-holding means including a normally energized hold-clear magnet for holding the gate in clear position, a circuit for said magnet controlled by said track 10 relay and including a normally energized high-resistance low-current-consuming delayed-action relay and a normally unenergized low resistance high-current-consuming delayed-action relay acting in series therewith for maintaining current 15 on the hold-clear magnet for a period after said track relay is actuated equal to the summation of the times for action of the two delayed-action relays, and motor operated means controlled by the gate arm and track relay for restoring the 15 gate arm to clear position after the train has passed.

8. Protective means for a highway railroad crossing including in combination; a support pivotally carrying a gate arm, a track relay de-energized on approach of a train to the crossing, a first slow-release relay in a circuit including a front contact of said track relay, a second slow-release relay in a circuit including a back contact of said track relay and a front contact of said first slow-release relay and having a snubbing circuit including a back contact of said first slow-release relay, a holding magnet for holding the gate arm in clear position and connected in a circuit including a front contact of said track relay connected in multiple with a front contact of each of said slow-release relays, warning signals on said support in circuits including back contacts of said track relay, said gate arm being constructed and arranged so as to move to lowered 30 or stop position by gravity when released by said holding magnet, a motor for raising the gate arm, and means operated by the gate arm for conditioning a circuit through the motor when the gate arm is down, said circuit being 35 completed by a front contact of said track relay when the track relay is restored to its normal condition characterized in that one of said warning signals is of the audible type, while the others are of the visual type, and further characterized in that lamps are carried on said gate 40 arm and a flasher relay is utilized and which is included in a circuit established by said track relay when de-energized, the flasher relay having contacts included in circuits for flashing alternately said visual signals on the support and on the gate arm, and still further characterized in that a circuit controller is connected to turn as the gate arm is lowered and raised, the controller having contacts closing a circuit through 45 said audible signal when the gate arm is in clear position and the track relay is de-energized and other contacts for maintaining said circuit through said flasher relay, and all of said visual signals after the track relay is re-energized following its de-energization period until the gate 50 arm is restored nearly to clear position.

HARRY C. SAMPSON.
